United States Patent Office

Des. 223,141

Patented Mar. 21, 1972

223,141

JUG OR SIMILAR ARTICLE

Earl E. Gilkeson, Carnegie, William C. Waterloo, York, and Richard L. Kennedy and Raymond E. Kennedy, Birdsboro, Pa., assignors to Graham Engineering Corporation, York, Pa.

Filed Oct. 26, 1970, Ser. No. 25,633

Term of patent 14 years

Int. Cl. D9—01

U.S. Cl. D9—41

FIG. 3

FIG. 2

FIG. 1

FIG. 1 is an elevational view of a jug or similar article showing our new design;

FIG. 2 is a top plan view; and

FIG. 3 is an elevational view looking from the right of FIG. 1, the opposite side being a mirror image of the side shown.

We claim:

The ornamental design for a jug or similar article, as shown and described.
